UNITED STATES PATENT OFFICE.

MARQUIS LATHAM, OF CHICAGO, ILLINOIS.

TROUSERS-STRETCHER.

SPECIFICATION forming part of Letters Patent No. 518,760, dated April 24, 1894.

Application filed May 25, 1893. Serial No. 475,427. (No model.)

To all whom it may concern:

Be it known that I, MARQUIS LATHAM, a citizen of the United States, residing at the city of Chicago, in the county of Cook, State 5 of Illinois, have invented a new and useful Trousers-Stretcher, of which the following is a specification.

Figure 1 shows my devices when extended to stretch the trousers throughout their whole 10 length. Fig. 2 shows the stretcher applied only to the knees of the trousers. Fig. 3 is a longitudinal section of the stretcher.

The object of the invention is to provide a simple, light, and yet strong and durable 15 frame, by means of which trousers may be stretched to take out the wrinkles from the waist band to the edges of the legs, and prevent bagging at the knees, and which shall combine in one simple part, the several means 20 heretofore employed for accomplishing the moving of the clamps through relatively long distances and getting the desired adjustment to keep the trousers taut while in the frame.

25 In the drawings, the device is shown as being made up of two duplicate oppositely arranged T-shaped sections, designated as a whole by A and B. The section A has a shank or longitudinal bar a with a cross bar a' at the outer 30 end secured thereto by bolts or screws, and a clamping bar a^2 adapted to be drawn toward the bar a' by screws and thumb nuts a^3 . The section B has a similar shank b , a cross bar b' , and a clamp bar b^2 adapted to be clamped 35 against the said cross bar by screws and thumb nuts b^3 . The two longitudinal bars slide on each other, each having secured to the inner end a strap c encircling the other thus bracing the two sections A and B firmly together 40 against lateral displacement, and yet allowing them to slide relatively to each other.

Mounted upon the inner face of the longitudinal bar a in a bearing C' is a screw rod C having the collars c^2 , c^3 to prevent the longitudinal movement relatively to the bearing, and also having the hand wheel C' , for rotating it. The screw works in a nut D which is secured to the end of the longitudinal bar b , there being a groove d in the inner face of 50 the said bar b , in which the screw C lies. It

will be seen that the screw rod is comparatively long, and extends nearly the length of the bar a . By means of the screw rod C and the nut D , the two sections can be slid apart until they assume the positions shown in Fig. 55 1, there always being a firm bracing provided by the straps c . Or when desired, the two sections can be drawn together to assume the positions shown in Fig. 2 where the device is applied to a pair of trousers to remove the 60 wrinkles and bagging at the knees only instead of from the whole length of the trousers as in Fig. 1. The threads on the screw C are of such a pitch, that the sections are rapidly moved relatively to each other. 65

I am aware that stretching devices for this purpose have been made with a bottom clamp and a single T-shaped part with a top clamp, the shank of the T-shaped part sliding through a socket in the lower or bottom 70 clamp, together with a short screw for exerting a pressure for stretching. But in this earlier device, the T-shaped part had to be made in several pieces in order to permit the length of the whole device to be adjusted for 75 different purposes, such adjustment being effected by slotting one of the parts and combining with them a thumb nut. In my case, the device is reduced to the utmost simplicity, and I can adjust the length of the whole 80 for different purposes, and also effect the stretching pressure by one and the same devices. The shanks of the parts can be light and yet strongly braced between the clamps, as each consists of a single piece. The clamps 85 are held much more firmly than if one of them be loose as to the longitudinal shank and provided with an aperture for the latter to slide through it.

I am also aware that stretchers have been 90 made of two overlapping T-pieces as is shown in Patent No. 492,279 to H. F. Featherstone. But there was no provision of a combined adjusting power device, and but a limited adjustment was possible. 95

Another type of earlier stretchers is illustrated in the British patent to Guy, No. 2,865, of 1877. Here use was made of two sections of wide relatively thick board which had to be separated to effect any stretching, one sec- 100

tion having guiding and bracing pins, and the other having apertures to receive the pins.

As above said, I provide a light device, which, although made of relatively thin pieces of wood, has great strength because of the bracing which can be provided for the overlapping shanks of the T-parts.

What I claim is—

A trousers stretching device composed of
10 two duplicate oppositely arranged T-shaped
sections, each section having a longitudinal
bar and transverse clamp bars, the longitudi-

nal bar of one section having a groove in its inner face, and a nut with its aperture in the longitudinal lines of the groove, and the other 15 longitudinal bar having secured to it a screw rod which lies in said groove, and between the said two longitudinal bars, substantially as set forth.

MARQUIS LATHAM.
